UNITED STATES PATENT OFFICE.

TAMAR G. HUMPHREY, OF HILL CITY, KANSAS.

VAPOR-BATH.

SPECIFICATION forming part of Letters Patent No. 441,761, dated December 2, 1890.

Application filed June 18, 1890. Serial No. 355,858. (No model.)

To all whom it may concern:

Be it known that I, TAMAR G. HUMPHREY, a citizen of the United States, residing at Hill City, in the county of Graham and State of 5 Kansas, have invented a new and useful Vapor-Bath, of which the following is a specification.

This invention has relation to vapor-baths; and the objects in view are to provide an eco- 10 nomically-constructed and simple apparatus of neat and tasteful design and adapted to serve as and have the appearance of a piece of furniture when not in actual use, and so constructed as to be adjustable to persons of 15 different heights and to thoroughly diffuse the steam throughout the apparatus.

With the above main and other minor objects in view the invention consists in certain 20 features of construction hereinafter specified, and particularly pointed out in the claims.

Referring to the drawings, Figure 1 is a perspective, the apparatus being shown as an ordinary table or buffet. Fig. 2 is a similar 25 view, the apparatus being in position for use as a bath. Fig. 3 is a vertical section of the same. Fig. 4 is a detail in perspective of the inner or movable casing. Fig. 5 is a detail in perspective of the chair or stool. Fig. 6 is a detail in perspective of the spraying-reser- 30 voir.

Like numerals of reference indicate like parts in all the figures of the drawings.

In practicing my invention I provide a case 1, preferably formed of wood and provided 35 with a metallic lining, said casing being mounted upon casters 2, whereby it is de- 40 signed to be removed with facility. The cas- 45 ing is covered ordinarily by a flat cover 3, or the same may be of any ornamental design, but in the present instance is designed to lend the appearance of an ordinary flat-topped table. From the opposite sides at one end of the casing there extend a pair of arms 4, in which is journaled a drum-shaft 5, provided 50 at one end with an operating-crank 6. Above the drum-shaft the edge of the casing is pro- 55 vided with, in this instance, three cut-away portions or recesses, and in each there is journaled a pulley 7, over which extend ropes or 60 chains 8, the outer ends of which are made fast to the drum at different points. The drum also is provided with a ratchet 9, the

teeth of which are engaged by a gravity-pawl 10, pivoted to the side of the casing.

11 designates the inner casing, which is 55 open at its top and bottom and has its oppo- 60 site side walls cut away, as shown, and a por- 65 tion of the adjacent end wall removed, so that a slanting front is presented. The inner 70 walls of this inner casing 11 are provided with 75 cleats 12 near their upper edges, and the front 80 portion of the casing is removably covered by a cover 13, provided with hooks 14, which take 85 into eyes 15, projecting from the edges of the 90 side walls. The top of the casing is covered 95 by a longitudinally-divided cover 16, the same being formed of two sections seated upon the aforesaid cleats 12, and at their adjacent 100 edges each cover is provided with a semicir- 105 cular opening, the two openings combining to 110 form a circular opening 17, designed to fit 115 around the neck of the patient. The front 120 wall of the casing 11, or rather that portion 125 which remains after the cutting away thereof, 130 is provided with a soap and sponge rack 18, 135 and the outer casing 1 is provided with a pair 140 of guides 19, in which is mounted for vertical 145 movement a sliding door 20.

The steam may be admitted to the appa- 15 ratus in any ordinary manner; but for the 160 purpose of convenience I prefer to employ a 165 small gasoline or gas stove 21, upon which is 170 mounted a suitable boiler 22, provided at its 175 top with a removable cover 23 and a steam- 180 escape 24. A pair of steam-pipes 25 lead from 185 the upper portion of the boiler, and by suit- 190 able bends or elbows are brought into register 195 with and enter a pair of openings 26, formed 200 in the side wall of the casings. The supply of 205 steam may be easily regulated by the admis- 210 sion of oil to the stove, whereby the heat may 215 be decreased or intensified, as required, and 220 also by a raising of the lid of the boiler, thus 225 permitting the steam to escape when being 230 formed too rapidly for the convenience and 235 safety of the patient.

A small opening 27 is formed in the top 16 240 at one corner, and through the same depends 245 a vertical pipe 28, the upper end of which 250 connects with a spraying-reservoir 29. The 255 lower end of the pipe 28 is provided with an 260 elbow 30, which rests upon and is supported 265 by a bracket 31, secured to the interior of the 270 inner casing 11, and connected to the elbow 275

is a flexible hose-section 32 of suitable length, which section terminates in a spraying-nozzle 33.

The bottom of the casing 11 is provided with 5 a surrounding flange 34, which has secured to its under side strips 35 of rubber packing, whereby a steam-tight connection is made between the inner and outer casings. The flange is provided on its opposite sides and at its 10 rear end with eyes 36, and above the side eyes the inner face of the casing is provided with pulleys 37. The central cord, chain, or rope 8 leading from the drum connects with the rear eye, and the two side cords or chains 15 pass over the guide-pulleys just mentioned and connect with the two side eyes, so that by a manipulation of the drum the inner casing may be raised and lowered in accordance with the height of the person undergoing 20 treatment.

The stool herein employed is preferably adjustable, and in this instance comprises the opposite pair of cross-bars 39, connected by suitable connecting-bars 40, the upper ends 25 of a pair of said bars 39 being connected by a transverse bar 41. The opposite pair of bars 39 terminate in tenons 42, and over the same is introduced a removable perforated bar 43. The fabric forming the seat 44 is connected to the two bars, and the bar 43 may be removed and a portion of the same rolled thereupon, as will be apparent, so that the area of the seat is decreased, which at the same time increases the height of the stool. 35 A foot-rest 45, the same being open, is secured to the floor of the outer casing, and under the same is passed the hose-section, which section is provided with a suitable cut-off 46, whereby the patient may turn on and off and 40 otherwise control the spray.

If desired, the spray or the vapor baths alone may be used, or both combined, the spray to follow the vapor-bath and serve to gradually lower the temperature of the patient until the same is normal, and thus obviate the liability of taking cold after leaving the bath.

To operate the apparatus the cover 3 is removed and the inner casing elevated, so as to 50 permit the entrance of the patient, which is accomplished through the sliding door 20 and by a removal of the covers 13 and 16. After the patient has been placed in position the cover 13 is replaced and the apparatus carefully adjusted so that the covers 16 will 55 enclose the neck of the patient when sitting. The covers 16 are now placed in position and a towel or other suitable packing placed about the neck of the patient, so as to practically 60 form a steam-tight joint and maintain the steam within the apparatus. The body may now be treated to a vapor-bath of heat and moisture and at the same time the patient breathe perfectly pure air. The water in the 65 boiler, and in fact that in the reservoir 29, may be either plain or medicated, as may be desired.

After the bath has been given the inner casing is lowered, the stove boiler and reservoir removed, together with the connecting-pipes, and the cover 3 replaced, whereby the apparatus is transformed from an unsightly bathtub to what might be considered a handsome piece of furniture. 70

Having described my invention, what I claim is— 75

1. In a bathing apparatus of the class described, the combination, with an outer closed casing, of an inner bottomless casing having a movable top mounted for vertical movement therein, a drum-shaft located at one 80 side of the outer casing, a pawl and ratchet and crank for operating the same, and a series of ropes or chains connected at their outer ends to the drum-shaft and over suitable guides and at their inner ends connected 85 to the inner casing, substantially as specified.

2. In a bathing apparatus of the class described, the combination, with an outer closed casing provided with a door and an inner vertically-adjustable bottomless casing 90 provided with a door, of mechanism for raising and lowering and locking in position said inner casing, substantially as specified.

3. In a bathing apparatus of the class described, the combination, with an outer closed 95 casing, of an inner bottomless casing provided at its lower edge with a flange having a packing forming a tight connection between the two casings, each of the casings being provided at one side with doors, and mechanism for adjusting said inner casing vertically within the outer casing, substantially as 100 specified.

4. In a bathing apparatus of the class described, the combination, with an outer casing 105 provided with a sliding door, of an inner casing provided at its front with an opening, and a removable cover formed in sections and provided at its adjacent edges with semi-circular openings adapted to fit the neck of 110 the patient, substantially as specified.

5. In a bath apparatus, the combination, with an outer closed casing and an inner sliding bottomless casing, each of said casings being provided with doors, and a suitable packing between the two casings, of a 115 pair of steam-pipes terminating in the outer casing below the inner casing, substantially as specified.

6. In a bathing apparatus, the combination, 120 with an outer casing having a removable cover, a door, and provided with a pair of bearing-arms, and at its upper edge above the arms with recesses, of an inner casing mounted for sliding in the outer casing, provided with a door and with a surrounding packing, eyes located at the opposite sides and at the rear end of the inner casing, pulleys mounted in the recesses and at each side of the inner casing, ropes or chains mounted 125 over the pulleys and connected at their inner ends to the eyes, a drum provided with a 130

ratchet mounted for rotation in the arms and provided with a crank for operating the same, the cords at their outer ends being connected to the drum, and a gravity-pawl pivoted to the casing and adapted to engage the ratchet, substantially as specified.

In testimony that I claim the foregoing as

my own I have hereto affixed my signature in presence of two witnesses.
